UNITED STATES PATENT OFFICE.

JOHN FÜRI, OF BÜMPLITZ, BERNE, AND JAMES RUBLEY, OF WÜLFLINGEN,
ZURICH, SWITZERLAND.

DESIGN FOR A STOCKING.

SPECIFICATION forming part of Design No. 14,018, dated July 3, 1883.

Application filed May 16, 1883. Term of patent 3½ years.

To all whom it may concern:

Be it known that we, JOHN FÜRI, of Bümp-
litz, canton of Berne, Switzerland, and JAMES
RUBLEY, of Wülfingen, canton of Zurich, Switz-
5 erland, have invented and produced a new and
original Design for Stockings, of which the
following is a specification.

The object of our invention is to provide a
new and improved design for stockings, where-
10 by the same will fit more closely and better
against the toes.

Reference is to be had to the accompanying
drawings, forming part of this specification, in
which similar letters of reference indicate cor-
15 responding parts in both the figures.

Figure 1 is a sectional plan view of our
newly-designed stocking. Fig. 2 is a perspec-
tive view of the same.

Heretofore the toe parts of stockings have
20 been made tapering equally from both side
edges of the foot toward the toe end of the
foot. Stockings made in this shape are strained
more or less in pulling on the foot so closely
that they fit well against the toes, and the re-
25 sult is that the stockings do not last long and
become torn at the toes very rapidly.

In our newly-designed stocking the toe end
of the stocking is beveled from one side of the
foot across to the other on one continuous line,
30 which can be made straight or curved. The
stocking for the left foot is beveled from the

right toward the left, and the stocking for the
right foot is beveled from the left toward the
right. That side part of the stocking fitting
against the outer side of the large toe is slightly 35
curved.

Having thus fully described our invention,
we claim as new and desire to secure by Let-
ters Patent—

1. The herein - described newly - designed 40
stocking, consisting of a stocking having its
toe end beveled from one side of the foot of
the stocking toward the other on a continuous
line, as set forth.

2. The herein - described newly - designed 45
stocking, consisting of a stocking having its
toe end beveled from one side of the foot of
the stocking toward the other on a continuous
line, and having that part of the side of the
foot of the stocking resting against the outer 50
side of the large toe slightly curved, as set forth.
